UNITED STATES PATENT OFFICE.

OTIS HEWES, OF LIME SPRING, IOWA.

WASHING-MACHINE.

SPECIFICATION forming part of Letters Patent No. 620,921, dated March 14, 1899.

Application filed October 29, 1898. Serial No. 694,972. (No model.)

To all whom it may concern:

Be it known that I, OTIS HEWES, a citizen of the United States, residing at Lime Spring, in the county of Howard and State of Iowa, have 5 invented a new and useful Washing-Machine, of which the following is a specification.

The invention relates to improvements in washing-machines.

The object of the present invention is to improve the construction of washing-machines and to provide a simple and comparatively inexpensive one capable of rapidly and thoroughly washing clothes and other fabrics without injuring them.

15 The invention consists in the construction and novel combination and arrangement of parts, as hereinafter fully described, illustrated in the accompanying drawings, and pointed out in the claims hereto appended.

20 In the drawings, Figure 1 is a perspective view of a washing-machine constructed in accordance with this invention. Fig. 2 is a longitudinal sectional view. Fig. 3 is a transverse sectional view. Fig. 4 is a detail perspective view of the cover.

Like numerals of reference designate corresponding parts in all the figures of the drawings.

1 Designates a semicylindrical washing-machine body provided with a curved sheet-metal bottom 2 and having a cover 3, supported upon horizontal ribs or flanges 4, arranged at the inner faces of the sides and ends of the body and provided at their upper faces with 35 rubber strips 5 to form a water-tight joint. The cover, which is composed of two sections, is hinged at the outer ends of the sections at 7 to the washing-machine body, and the said sections are adapted to swing outward to open 40 the washing-machine.

The washing-machine body is provided at opposite sides with suitable bearings, in which is arranged a transverse shaft 8, having flattened ends 9, which detachably engage recesses 10 of a frame or stand 11, whereby the shaft is held stationary. The shaft, which is stationary, extends across the washing-machine body and is provided between the sides of the same with a rigid depending presser or 45 pounder 12, which engages the clothes when the washing-machine body is oscillated. The shaft 8 and the depending pounder or presser

12, which are rigid with each other, may be constructed either of wood or metal.

The stand, which may be constructed in any 55 suitable manner, is provided at opposite sides with inclined standards 13, connected at their lower ends by cross-bars 14 and having their upper terminals secured to blocks 15, which are provided with the said recesses 10. When 60 the ends of the shaft are arranged in the recesses of the frame or stand, the washing-machine body is supported for oscillation, and it is provided with a suitable handle 16. The lower end of the handle is fitted in the 65 socket 17, consisting of a casting which is provided with suitable arms or ears 18, perforated for the reception of fastening devices for securing the casting to the washing-machine body. 70

The washing-machine body is provided at its ends with transverse ribs 19, triangular or tapering in cross-section and preferably formed integral with the end flanges 4 of the washing-machine body. The transverse ribs 75 are perforated for the passage of water, and when the washing-machine body is oscillated its ends are carried alternately toward the presser or pounder 12, and the clothes are squeezed between the same and the ribs 19 80 and perforated plates 20, which are mounted on the cover at the ends thereof. The upper portion of the pounder or presser is provided with an opening 21, and the lower portion is perforated for the passage of water expelled 85 from the clothes.

The plates 20, which may be constructed of wood, metal, or any other suitable material, are provided with perforations and are spaced from the cover by tapering strips or blocks 90 22, which taper toward the center of the cover, their larger ends being disposed toward the ends of the cover. The lower edges of the tapering blocks or strips 22 are inclined and diverge downwardly, and the perforated 95 plates, which are offset from the cover, are disposed at an inclination. The clothes to be washed are placed within the washing-machine body at opposite sides of the presser or pounder, and when the body is oscillated 100 and the clothes squeezed the water is expelled from them and forced through the perforations of the plates, the presser or pounder, and the ribs, and it escapes through the open-

ing of the presser or pounder and through the passages formed by offsetting the plates from the cover.

The washing-machine, which is exceedingly simple and inexpensive in construction, is easily operated and is capable of quickly removing the dirt and stains from clothes. The clothes are squeezed and pressed and thoroughly subjected to the action of hot water and suds, and the operator is enabled to exert the desired amount of pressure on them. As the washing-machine body and the clothes are oscillated the latter are thoroughly and uniformly operated on and cannot collect and remain at one end of the body out of reach of the washing mechanism.

Changes in the form, proportion, and minor details of construction may be resorted to without departing from the spirit or sacrificing any of the advantages of this invention.

What is claimed as new is—

1. A washing-machine comprising a frame or stand, an oscillating washing-machine body, a stationary shaft mounted on the frame or stand and supporting the washing-machine body, a stationary presser or pounder arranged within the body and depending from the shaft, and the inclined perforated plates spaced from the lower face of the cover and forming passages, said inclined plates being

carried out of the body by the cover when the latter is opened, substantially as and for the purpose described.

2. A washing-machine comprising a frame or stand, a stationary shaft mounted on the frame or stand, an oscillating washing-machine body journaled on the shaft and provided at its ends with transverse ribs having perforations, a rigid pounder or presser depending from the shaft, a cover provided on its lower face with tapering blocks or strips arranged in pairs, and the inclined perforated plates secured to the blocks or strips and spaced from the cover, substantially as described.

3. The combination of an oscillating washing-machine body, a stationary presser or pounder arranged within the washing-machine body, a cover composed of sections hinged at their outer ends to the body, and perforated plates mounted on and spaced from the lower faces of the sections of the cover, substantially as described.

In testimony that I claim the foregoing as my own I have hereto affixed my signature in the presence of two witnesses.

OTIS HEWES.
